[57] CLAIM

The ornamental design for a cutting board, as shown
and described.

DESCRIPTION

FIG. 1 is a top, front, and left side perspective view of
a cutting board showing my new design;

FIG. 2 is a top plan view; and

FIG. 3 is a bottom plan view thereof.

The side and rear view opposite that disclosed in FIG.
1 are similar thereto.

FIG.1.

FIG.2.

FIG.3.
